UNITED STATES PATENT OFFICE.

ELBERT E. ALDERMAN, OF PORTVILLE, NEW YORK.

ADVERTISING DEVICE.

SPECIFICATION forming part of Letters Patent No. 367,946, dated August 9, 1887.

Application filed March 5, 1887. Serial No. 229,817. (No model.)

To all whom it may concern:

Be it known that I, ELBERT E. ALDERMAN, a citizen of the United States, residing at Portville, in the county of Cattaraugus and State 5 of New York, have invented certain new and useful Improvements in Advertising Devices; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 This invention relates to advertising devices which display changing or movable signs for windows, stores, or other places, the object being to utilize an easel or similar ornamental stand for that purpose by utilizing the front legs 20 as rollers on which the cloth, paper, or canvas strip winds and unwinds, and on which are printed, painted, or otherwise arranged announcements, advertisements, &c.; and the invention as constructed will be understood 25 by reference to the following specification and claims.

In the drawings, Figure 1 is a side elevation of the device; Fig. 2, a front elevation of the device; Fig. 3, a perspective of the device; 30 Fig. 4, a cross-section through line $x-x$ of Fig. 2.

$a a$ represent the two front legs of an easel or frame, being legs and rollers combined by being made round, and fitting into the hollowed-out ends of two ornamental longitudinal cross-pieces, $d d$, and held in place by metal straps $e e$. The space s between the two cross-pieces $d d$ is occupied by the advertising-strip b , the ends of which are fastened to the 35 leg-rollers $a a$ and wound around them. On 40 this strip is put the announcements of the day or week of any special article for sale, or

line of goods, or pictorial representation, and when it has been exposed as long as desired it is wound around one leg-roller and unwound 45 from the other by merely taking the legs in hand and turning them as desired until the old sign is wound up and the new space exposed for the succeeding one. When all wound up on one side, it is then gradually 50 wound back, reproducing the old signs, or new ones in their places.

Of course, the various uses of this panoramic display-sheet are almost unlimited as to 55 subjects and objects.

g is the rear leg of the easel; $h h$, pegs. $c c$ are side shields or covering-pieces, ornamental, if desired, and designed to cover and protect the rolled-up or unrolled portions of the belt or strip b , besides hiding that part from view. 60

The great advantage of this device is its simplicity, combining with an easel the movable strip b , and utilizing the legs as rollers.

I claim—

1. The easel advertising device consisting 65 of the cross-pieces $d d$, having their ends hollowed out, the combined legs and rollers $a a$, rounded to partly recess in said cross-pieces, the belt or advertising-strip b , the ends fastened to and winding and unwinding on said 70 round legs, all substantially as specified.

2. The combination of the easel consisting 75 of the legs $a a$ partly recessed in cross-pieces $d d$, the metal strips $e e$, the advertising-strip b , attached to the roller-legs, and the covering side pieces, $c c$, all arranged as and for the purpose specified.

In testimony whereof I affix my signature in presence of two witnesses.

ELBERT E. ALDERMAN.

Witnesses:

J. R. DRAKE,
Wm. TRENKLE.
